US0D1020750S

(12) **United States Design Patent** (10) **Patent No.:** **US D1,020,750 S**
(45) **Date of Patent:** **** Apr. 2, 2024**

(54) **MODULAR BIOMETRIC STATION**

(71) Applicant: **Alclear, LLC**, New York, NY (US)

(72) Inventors: **Matthew Wilkins**, Brooklyn, NY (US); **Austin Puckett**, Brooklyn, NY (US); **Raymond Protasiewicz**, Whippany, NJ (US); **Aditi Vyas**, Phoenix, AZ (US); **Travis Baldwin**, Bristol (GB); **Gregory Sparks**, New York, NY (US); **Navni Garg**, New York, NY (US); **Nicholas Oxley**, Brooklyn, NY (US)

(73) Assignee: **SECURE IDENTITY, LLC**, New York, NY (US)

(**) Term: **15 Years**

(21) Appl. No.: **29/798,874**

(22) Filed: **Jul. 12, 2021**

Related U.S. Application Data

(63) Continuation of application No. 17/319,939, filed on May 13, 2021.

(57) **CLAIM**

We claim the ornamental design for a modular biometric station, as shown and described.

DESCRIPTION

FIG. 1 depicts a front view of a modular biometric station with standalone end caps and a core unit.

FIG. 2 depicts a top view of the modular biometric station of FIG. 1.

FIG. 3 depicts a side view of the modular biometric station of FIG. 1; and,

FIG. 4 depicts a front isometric view of the modular biometric station of FIG. 1 with the standalone end caps removed.

Broken lines depict portions of the modular biometric station that form no part of the claimed design.

1 Claim, 3 Drawing Sheets
